UNITED STATES PATENT OFFICE

101,023

DESIGN FOR MACHINE-KNIT FABRIC

Doris H. Cavanaugh, Newton, Mass.

Application July 11, 1936, Serial No. 63,801

Term of patent 14 years

To all whom it may concern:

Be it known that I, Doris H. Cavanaugh, a citizen of the United States, residing at Newton, county of Middlesex, and State of Massachusetts, have invented a new, original, and ornamental Design for Machine-Knit Fabric, of which the following is a specification, reference being had to the accompanying drawing, forming part thereof.

My new design, reference being had to said drawing, has as a dominant feature the recurring differentially grouped overlaid or incrusted appearances of the narrow-fabric component in a plurality of knitting wales and courses, substan-

tially recurrent areas being indicated upon the drawing in the typical area bounded by the vertical lines *a* and *b* and by the horizontal lines *c* and *d*, and in the corresponding area bounded by the vertical lines *a'* and *b'* and by the horizontal line *d* and *e*, and as to which areas the point *ac* of the first is repeated at *a'd* of the second.

The single figure of the drawing is a plan view of a piece of machine-knit fabric embodying the design.

I claim:

The ornamental design for machine-knit fabric, substantially as shown and described.

DORIS H. CAVANAUGH.
